His Attorney.

UNITED STATES PATENT OFFICE

2,092,652

ELECTRIC CIRCUIT INTERRUPTER

Ezra B. Merriam, Swarthmore, Pa., assignor to
General Electric Company, a corporation of
New York

Application December 24, 1934, Serial No. 758,925

4 Claims. (Cl. 200—150)

My invention relates to electric circuit interrupters of the single pole type wherein the circuit is opened within a pressure chamber containing an arc extinguishing liquid such as oil, and the pressure generated by the resulting arc is utilized to effect expulsion of liquid from said chamber for extinguishing the arc.

Electric circuit interrupters of the aforesaid type are commonly known as explosion chamber breakers and have long been used for interrupting high voltage power circuits. A well known form of explosion chamber breaker comprises an insulated explosion pot forming the explosion chamber having at one end a fixed contact structure. A coacting contact rod is movable into said chamber through an exhaust opening or throat at the opposite end of said chamber. The explosion pot and contact structure are immersed in a suitable insulating and arc-extinguishing liquid such as oil, the oil filling the explosion chamber.

When the contacts are separated to open the circuit the well known explosion chamber effect is obtained; that is, the pressure generated within the explosion chamber by arc current causes a blast of oil through the arc as the movable contact passes through said throat. The arc is generally interrupted at that point.

In modern electric power transmission systems operating at commercial frequencies, it is highly desirable to limit the duration of arcing and hence the length of the arc. The conventional type of explosion chamber above described, however, utilizes the interrupting action of the blast mainly after the arc has been drawn throughout the length of the explosion chamber, i. e. at the throat. Although this results in effective interruption of arcing operating requirements may necessitate even faster interrupting time.

A principal object of my invention is the provision of an improved single pole electric circuit interrupter of the explosion chamber type, as contrasted with an interrupter having two or more breaks in the same chamber, which is simple and inexpensive in construction and which is effective to decrease the arcing time for breakers of the aforesaid type.

In accordance with my invention in an operative form thereof, the explosion pot or chamber is provided with an exhaust opening or port extending substantially transversely of the path of the arc, as distinguished from the throat opening through which the movable contact may operate. In this form, the width of the chamber corresponds roughly to its length so that appreciable arcing space is involved. The arc may be drawn

eccentrically with respect to the longitudinal axis of the chamber so as to be adjacent and transverse of said exhaust port, the remaining portion of the explosion chamber serving as an oil reservoir. I have found that an explosion chamber breaker so constructed is effective to interrupt the arc well within the explosion chamber so that the arcing time is limited to a few half cycles.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view, partly in section, of the circuit interrupting means of a single pole explosion chamber oil circuit breaker embodying my invention and Figs. 2, 3, 4 and 5 are similar views illustrating various single pole forms my invention may assume.

Fig. 1 illustrates the circuit interrupting means of one pole of an oil circuit breaker comprising an explosion pot 1, relatively movable contacts 2 and 3, and an insulating and arc extinguishing liquid 4, such as oil, in which the explosion pot and contact structure are immersed. It shall be understood that the term "oil" as used herein-after is intended to comprehend a suitable arc-extinguishing liquid. The explosion pot 1 is suitably formed of a mechanically strong insulating material, such as a laminated structure impregnated with a phenolic condensation product, and is secured in depending relation to a flange 5 of the stationary adapter 6. The lead-in conductor 7 is insulated with respect to the circuit breaker tank (not shown) by the usual high voltage insulating bushing 8 at the lower end of which, at 9, is secured the contact adapter.

The fixed contact structure 2 comprises a butt contact resiliently biased, as by a spring 10, towards a lower limiting position into engagement with an annular arcing portion 11. The butt contact is electrically connected through flexible conductors 12 to the contact retaining structure 13 which is electrically connected to the adapter 6 and hence to the lead-in conductor 7.

At high voltages an insulating cylindrical shield 14 is mounted on a flange 15 which is supported, as at 16, by the explosion pot securing means.

The movable rod contact 3 is mounted at one end of a bridging member 17, the other end of which carries the contact of the other and similar pole of the breaker (not shown). The contact 3 is movable through an exhaust opening or throat

18 formed in the lower end of the explosion pot opposite the fixed contact 2. As will be noted, the movable contact enters the explosion chamber eccentrically with respect to the longitudinal axis 5 of said chamber for coaction with the fixed contact 2.

For the purpose of effecting interruption of the circuit within the explosion chamber and while the arc is still comparatively short, an exhaust port 19, which is restricted as compared with the volume of the chamber, is formed in a lateral wall of the explosion pot adjacent and opposite the path of the arc. As illustrated, the arc, generally indicated at 20, is drawn transversely of the exhaust port 19 while the arc is comparatively short. I have found that with this arrangement the arcing time is appreciably reduced and that the arc is interrupted well within the chamber as compared with interruptions at or near 20 the throat 18.

One explanation of the improved interrupting characteristics of this form of explosion chamber may be based on the fact that the arc, which by reason of its contact with the oil generates 25 pressure within the explosion chamber at a high rate, is subjected as indicated to the wash of the oil as it is expelled from the chamber through the lateral port 19.

In view of the fact that the throat 18 is still 30 practically closed by the movable contact 3, oil by reason of the arc pressure within the explosion chamber must exhaust at a high rate through the port 19 into the exterior free oil body. The lines of flow converging toward the port 19 35 traverse the arc which is swept toward the port and extinguished at that point while the movable contact 3 is still within the explosion chamber.

The eccentric positioning of the movable contact within the explosion chamber not only provides an appreciable oil storage space opposite 40 the exhaust port in the event of heavy short circuits, but also advantageously locates the arc with respect to the lateral exhaust port 19. In the event that the arc is not interrupted within 45 the chamber the usual interrupting effect is also obtained at the throat 18.

In Fig. 2 the explosion pot 1 is fundamentally similar to that of Fig. 1. In this case the contact 3 moves centrally of the explosion chamber 50 through the lower throat 18. The lateral port 19 is positioned in a side wall of the explosion pot as above described, and an insulating baffle 21 projects horizontally from the inner wall of the explosion pot beneath the port 19. The purpose 55 of this baffle is to direct the oil flow from the explosion chamber so as to intensify the flow across the arc. The operation is generally similar to Fig. 1.

Fig. 3 illustrates a simple application of my 60 invention to circuit interrupters of the single break type wherein the movable contact member is elevated to open circuit position. In this arrangement the circuit breaker tank 22 is filled with oil to the level indicated, the tank having 65 suitable insulating lining 23. A fixed contact 24 is mounted at the lower part of the tank, and a movable rod contact 25 is guided for vertical reciprocal movement with respect to contact 24. The contacts coact within an interrupting chamber 70 26 formed by a strong insulating cylinder 27 having a reinforcing lining 28. An insulating disk 29 forms the upper wall of the interrupting chamber. The rod contact 25 is guided within a bushing 30 forming a throat at the upper wall 75 of the interrupting chamber.

For the purpose of obtaining the improved interrupting characteristics above described, the chamber 26 is provided with a lateral port at 31 substantially opposite the point of contact separation opening into the annular free space 32 5 formed between the insulating cylinder 27 and the breaker casing. Accordingly, upon separation of the contacts 24 and 25 the arc pressure generated within the chamber 26 is effective to expel oil at a high rate through the port 31 for 10 interrupting the arc at that point. In this arrangement which is particularly adapted for comparatively low voltage power circuits, the arc is generally interrupted after a short vertical travel 15 of the contact 25 beyond the port so that there is no necessity for moving said contact out of the interrupting chamber 26.

In Fig. 4 the explosion pot 1 is provided with the lateral port 19 at a point appreciably beyond 20 the initial formation of the arc. As illustrated, the lateral port 19 is adjacent the throat 18 so that, although the arc length is increased, the oil flow across the arc is concentrated at the lower part of the chamber and is greatly intensified as 25 the contact 3 moves into the throat 18. A powerful cross blast effect is thereby obtained which has been found to be very effective in interrupting heavy short circuits.

In Fig. 5 the explosion pot 1 is provided with 30 an expulsion arc chute 33 mounted within the lateral port 19 and arranged to form a channel for receiving the arc. The expulsion chute 33 may be suitably formed of plates of insulating material, the chute opening downwardly into the oil body at 34. The chute preferably extends within the explosion chamber so that the movable contact is drawn between the side extensions of the chute. 35 Accordingly, the arc drawn is within or at the entrance 33' of the chute and is confined within the path of oil flow as indicated so that it is swept 40 in a definite direction by the oil blast from the explosion chamber. It will be apparent, of course, that the expulsion chute may exhaust directly 45 outwards from the explosion chamber. Where, however, the breaker tank wall is close to the explosion chamber downward venting of the expulsion chute may be preferred.

In the above-described arrangements for carrying 50 my invention into effect, conventional contact structure is employed for interrupting the circuit. However, other suitable circuit interrupting means may be employed, the fundamental concept being that of forming a break and drawing an arc within an explosion chamber, or its equivalent, transversely of a lateral exhaust port 55 through which oil from the explosion chamber is expelled by the arc pressure at the aforesaid break to cause interruption of the arc.

It should be understood that my invention is 60 not limited to specific details of construction and arrangement hereof herein illustrated, and that changes and modifications may occur to one skilled in the art without departing from the spirit of my invention.

What I claim as new and desire to secure by 65 Letters Patent of the United States is:

1. A single pole electric circuit interrupter comprising an insulating casing forming a substantially undivided pressure confining chamber containing oil, the width of said chamber corresponding approximately to its length, a fixed contact disposed in said chamber and a coacting contact movable in said chamber for opening the circuit at said fixed contact, said casing having an exhaust port located adjacent to and at one side of the 70 75 75

- path of the arc drawn by said movable contact, the size of said arc chamber bearing such relation to said arc path and to said exhaust port respectively that said arc is appreciably spaced from the walls of said casing, and the arc pressure generated within said casing causes expulsion of oil at high velocity through said exhaust port for interrupting the arc at that point. 5
2. A single pole electric circuit interrupter comprising an insulating pot forming a substantially undivided pressure confining chamber containing oil, the width of said chamber corresponding approximately to its length, a fixed contact disposed at one end of said chamber and a coacting rod contact movable along a path eccentric with respect to the longitudinal axis of said pot for opening the circuit at said fixed contact, said pot having an exhaust port located adjacent and transversely of said arc path, the size of said arc chamber bearing such relation to said arc path and to said exhaust port respectively that said arc is appreciably spaced from the walls of said pot, and the arc pressure generated within said pot causes expulsion of oil at high velocity through 10 said exhaust port for interrupting the arc at that point. 15
3. A single pole electric circuit interrupter comprising an insulating pot forming a substantially undivided pressure confining chamber containing oil, the width of said chamber corresponding approximately to its length, a fixed contact disposed 20
- 25
- 20
- 25
- 30
- within said chamber and a coacting contact movable in said chamber for opening the circuit at said fixed contact, said pot having an exhaust port located substantially transversely of the path of movement of said movable contact adjacent the point of initial separation of said contacts and initial formation of the arc, the size of said arc chamber bearing such relation to said path and to said exhaust port respectively that the arc is appreciably spaced from the walls of said pot and the arc pressure generated within said pot by said initial arcing causes expulsion of oil at high velocity through said exhaust port for interrupting the arc at that point. 10
4. A single pole electric circuit interrupter comprising an insulating pot forming a pressure confining chamber containing oil, a fixed contact disposed in said chamber and a coacting contact movable through said chamber for opening the circuit at said fixed contact, said pot having an exhaust port located at one side of the path of the arc drawn by said movable contact, and means forming an arc chute in said chamber communicating with said pot including spaced insulating members between which said arc is drawn, the size of said arc chamber bearing such relation to said exhaust port that the arc pressure generated within said pot causes expulsion of oil at high velocity through said chute and exhaust port for interrupting the arc within said chute. 15 20 25 30
